UNITED STATES PATENT OFFICE.

MALCOLM A. BEESON, OF STILLWATER, OKLAHOMA.

DESIGN FOR A GRAVE MARKER.

Application filed May 17, 1928. Serial No. 26,713. Term of patent 14 years.

To all whom it may concern:

Be it known that I, MALCOLM A. BEESON, a citizen of the United States, residing at Stillwater, in the county of Payne and State of Oklahoma, have invented new, improved, and original Design for Grave Markers, of which the following are specifications, reference being made to the accompanying drawings, forming a part hereof.

elevation and

Figure 2 is a side view showing my new design.

I claim:

The ornamental design for a grave marker as shown.

In witness whereof, I have hereunto set my hand this ninth day of April, 1928.

M. A. BEESON.
